VENDING MACHINE FEED MECHANISM

Harry S. Benjamin, Utica, N. Y.

Application November 25, 1931
Serial No. 577,288

7 Claims. (Cl. 194—97)

This invention relates to means for preventing the unauthorized operation of a vending machine of the type described in my application, Serial Number 436,982, filed March 19, 1930, since patented March 29, 1932, No. 1,851,081, by means of the insertion in such a machine, of a wire or other tool for operating the vending or merchandise discharge members of such machine and which members are normally rotated through the medium of suitable mechanism including a power transmitting member adapted to be rotated in one direction only, by power applied thereto when such mechanism is released by the insertion of a coin in the machine.

15 A further object is to provide means for transmitting motion from said power transmitting member to another member arranged to be driven thereby, in such a manner that said power transmitting member is always connected to said member which is to be driven thereby, to transmit motion thereto, but which connection is such that the driven member will be immediately locked and held against turning, upon the application of any turning power to said driven member or parts connected thereto, other than through the medium of said power transmitting member and its driving mechanism when said mechanism is released by the insertion of a coin in the machine.

20 It is also an object to provide means for the purpose, which means is simple in construction, positive in operation, and may be readily embodied in a vending or other machine of the class or type disclosed in my said application above referred to.

25 With the above and other ends in view, the invention consists in the matters hereinafter set forth and more particularly pointed out in the appended claims, reference being had to the accompanying drawings in which

30 Fig. 1 is a transverse vertical section through the lower end portion of a vending machine illustrative of an embodiment of the invention;

35 Fig. 2 is a horizontal section, substantially upon the line 2—2 of Fig. 1;

40 Fig. 3 is a sectional detail, substantially upon the line 3—3 of Fig. 1;

45 Fig. 4 is a sectional detail substantially upon the line 4—4 of Fig. 2; and

50 Fig. 5 is a sectional detail substantially upon the line 5—5 of Fig. 2, with parts broken away and in section to disclose the construction.

Enough of the machine disclosed in my said pending application above referred to, is shown in the accompanying drawings to illustrate the application of the present invention thereto and

the purpose and manner in which it operates in connection therewith, the principal parts of the delivery mechanism and their operation, being described as follows:

The machine includes any suitable form of casing 1 for enclosing the vending mechanism and provided with a detachable back 2 upon which said mechanism is mounted, said back being arranged to support, preferably, four rectangular chutes or magazines 3 for holding merchandise in the form of small packages shown in Fig. 1 in one of said chutes, in superposed relation within said chutes.

These packages are removed, one at a time from the lower ends of these chutes by means of 70 rotatable feed members or blocks 4, one of said feed blocks being located directly beneath each chute and each formed with a notch or recess 5 of a shape and size to receive a single package and, when the block is rotated, discharge the 75 same into a single chute 6 leading to a delivery cup 7 opening through a wall of the casing.

Each of the feed blocks is secured to a shaft 8 and secured to the rear end of each of said shafts, is a gear 9, these gears being in mesh 80 with each other so that all of said blocks will be turned simultaneously an equal distance. The four blocks are secured to their shafts in such relative positions that when the recess 5 in one block is at the upper side thereof, the recess in the next block is at one side, the recess in the next block of the series is at the bottom or in discharge position and the recess in the last block is at the other side. Therefore at each quarter rotation of the several blocks, a package will be 85 discharged. It will be understood, however, that any suitable arrangement and construction of discharge means may be provided, as well as one or more chutes, this arrangement being merely 90 illustrative of one construction of machine to 95 which the present invention may be applied.

To actuate the train of gears 9 and thus simultaneously rotate all of the blocks 4, a plate 10 is mounted on the back wall 2 of the casing for vertical movement thereon, by means of a stud or screw 11 passing through a vertical slot 12 in said plate and located at one side of said plate is a horizontal shaft 13 mounted at its rear end on the casing wall 2 and at its forward end in the rear wall of the chute 6, there being sleeved upon said shaft, a power transmitting sleeve 14 to the rear end of which sleeve, adjacent the plate 10, is secured or formed integral therewith, a ratchet wheel 15, said sleeve being formed at its forward end, with an outstanding circular flange 110

16 to abut the rear side of a circular block 17 rigidly secured by a pin 18 (see Fig. 3) to said shaft 13, which block is surrounded by a ring 19 which ring is held in a fixed position by a stud 5 20 on the adjacent side wall of the chute 6. Secured to the flange 16 on the power transmitting sleeve 14, is a stud 21 provided with a sleeve and forming a roller which projects into a notch 22 (see Fig. 5) cut in the periphery of 10 the circular block 17, and a light coiled spring 23 is interposed between one side of this roller 21 and the end wall of the notch, to exert a force to normally hold the parts with said roller pressed toward the reduced end of said notch. Secured to 15 or formed integral with the forward end of said shaft 13, is a gear 24 in mesh with an idler gear 25 which in turn is in mesh with one of the gears 9 of the train of gears on the shafts 8 on which shafts the feed blocks 4 are secured.

20 To transmit motion from the plate 10 to turn the ratchet 15 and power transmitting sleeve 14, an arm 26 is mounted for free turning upon the rear end of the shaft 13 adjacent said ratchet and at its free end, this arm carries a stud 27 which 25 projects through and is free to slide within a horizontal slot 28 in said plate 10. Pivotedly mounted upon this stud 27 is a pawl 29 having a tail portion to which a coiled spring 30 is attached to normally exert a turning force upon 30 said pawl and hold the same against the periphery of the ratchet 15. A stop pin 31 on the back wall of the casing is positioned so that the engaging end of the pawl will be caught between said pin and wheel when the plate 10 is at the 35 upper end of its stroke and the pawl is in a horizontal position and lying within one of the notches of the ratchet wheel. The ratchet wheel is thus locked against turning and the plate is limited in its up movement, not only by the length 40 of the slot 12 but also by the said stud or stop pin 31.

45 Turning movement of the ratchet 15 and sleeve 14 in a direction opposite to that in which they are turned by said pawl 29, is positively prevented and the ratchet accurately positioned, by means of a latch bar or plunger 32 longitudinally movable in a bracket 33 on the back wall 2, and provided with a head 34 to engage in a notch of said ratchet, said head having an inclined top 50 face so that the ratchet when turned by said pawl 29, will slide past said head, forcing the plunger longitudinally, against the action of a spring 35 sleeved on said plunger between its head and said bracket, said spring thus normally holding said plunger engaged in a notch 55 of the ratchet and positively preventing turning movement of the ratchet in a direction opposite to that in which it is turned by said pawl, due to the engagement of said head with a straight or radial side face of the ratchet notch.

60 To actuate the slide plate 10 and to guide the lower end thereof, a power shaft 36 (see Fig. 1) is mounted to extend in parallelism with said shaft 13 through a vertical slot in the lower end 65 portion of said plate, and this shaft is extended through an opening in the casing wall and is provided with suitable means (not shown) for turning the same manually. On this shaft is a cam member indicated at 37 in Fig. 1, which is arranged in a suitable manner to lift said plate and through such movement of said plate, actuate the delivery mechanism.

75 To normally hold this shaft 36 against turning more than a limited distance and thus prevent the operation of the delivery mechanism to de-

liver merchandise, a circular head indicated at 80 38 in Fig. 1, is connected to said shaft and an arm or bar 39 is positioned with its lower end in the path of shoulders 40 on said head, suitable coin controlled mechanism being operative to withdraw this bar 39 from the path of said shoulders, when a good coin is inserted in the machine, all as fully shown and described in my before mentioned pending application.

To control the downward movement of the 85 actuating plate 10 so that if no coin or a coin other than a good one be inserted in the machine, the plate will be stopped to prevent the delivery of merchandise, coin controlled mechanism is provided, this mechanism including a laterally extending lug 41 on the upper end of said plate 10 (see Fig. 1) to engage a stop member 42 which is pivotally supported to swing into and out of the path of said lug, said stop member being adapted to be swung by a bar 43 pivotally connected therewith at its upper end, the lower end of said bar being pivotally connected to the free end of a swinging arm 44 pivotally supported at its opposite end upon the lower end of a coin chute 45 and provided with a notch 100 or shoulder 46 to engage a stop arm 47 having a laterally bent end portion 48 adapted to be projected through a side opening in the chute across the path of a coin passing down said chute. To swing said arm 44 and bring it into 105 latched or normal position with its end 48 retracted from across said chute, suitable means is provided on the shaft 36, all as fully shown and described in my pending application before referred to.

110 As set forth in said pending application, other mechanism is provided in connection with the coin controlled mechanism, for detecting spurious coins and other substitutes, so that when substitutes for good coins are inserted, the machine 115 will not operate to deliver merchandise, all as fully set forth and described in my pending application, the drawings of the present application disclosing only just sufficient parts of such coin controlled mechanism to identify the present type 120 of machine and show that it embodies such mechanisms, the present invention relating to means in such a machine and in combination with such mechanisms, for preventing the delivery mechanism of the machine from being operated by a wire or other device inserted and manipulated to engage and move parts of the delivery mechanism, to deliver merchandise without the insertion of a good coin.

125 By inserting suitable motion transmitting 130 means between the delivery mechanism for effecting the delivery of the merchandise, and the power transmitting sleeve 14 which is operated by the operation of the normally locked manually operated shaft 36, and which shaft is adapted to 135 be unlocked, by means of the coin controlled mechanism, as herein set forth, said delivery mechanism is prevented from being operated by a wire or other tool inserted through the open end of the merchandise chute 6 and up into engagement with one of the delivery blocks 4 or gears 9 connected therewith. This motion transmitting means comprises the circular block 17 which is secured to the shaft 13 upon which the power transmitting sleeve 14 is sleeved for independent rotation thereon and which block is formed with the peripheral notch 22 to receive the stud roller 21 which is carried by said flange 16 on said sleeve, the said block being surrounded by the fixed or stationary ring 19, so that when- 140 145 150

ever the sleeve is turned in a clockwise direction, it will move said stud roller toward the large end of the notch 22 against the action of the light spring 23, and coming into engagement with 5 said end of the notch, will carry the block around with it and through the firm connection of this block with the shaft 13, will transmit motion to the gear 24 on the end of said shaft and thus transmit motion to the gears 9 to rotate the 10 delivery blocks 4 and deliver merchandise. This connection is therefore always operative to transmit motion from said sleeve to the delivery mechanism, but should an attempt be made to turn said gears or delivery blocks, in a direction 15 which will turn the block 17 in a clockwise direction, the roller 21 will immediately be wedged within the small end of the notch between said block and the fixed ring 19 and prevent rotation of the gear 24, and as the ratchet 15 and consequently the sleeve 14 are at all times prevented 20 from counter clockwise rotation by the plunger 32, the turning of the delivery blocks in either direction is prevented at all times except when the sleeve 14 is turned through the medium of 25 the coin controlled power transmitting mechanism after the unlocking of said mechanism by the insertion of a good coin.

Therefore the operation of the delivery mechanism to deliver merchandise is positively prevented at all times except through the medium 30 of the power transmitting means after the same has been released by the coin controlled mechanism.

Obviously the present invention relates to the 35 combination, in a vending machine, of coin controlled power transmitting mechanism, delivery mechanism, and interposed means for transmitting motion from said coin controlled mechanism to said delivery mechanism, which means 40 is effective to prevent such transmission of motion when said delivery mechanism is operated by other than said coin controlled mechanism, and applies to any form or arrangement of coin controlled power transmitting mechanism and 45 also any suitable form or arrangement of delivery mechanism in a vending machine employing such mechanisms.

Having thus fully described my invention, what I claim is:—

- 50 1. In a machine of the character described including motion transmitting coin controlled mechanism and merchandise delivery mechanism, of motion transmitting means interposed between said mechanisms and operative at all 55 times to transmit motion from said coin controlled mechanism to said delivery mechanism when said coin controlled mechanism is operative and adapted to prevent the transmission of motion between said mechanisms when said 60 coin controlled mechanism is inoperative, said means including an element movable by the coin controlled mechanism and limited to movement in one direction by said mechanism, a second element movable with the delivery mechanism, said 65 elements being co-operative in driving the delivery mechanism during permitted movement of the first element when the coin-controlled mechanism is operative, and a stationary guard member for said elements, said guard member being inactive in the control of element movements when the coin-controlled mechanism is operative.
- 70 2. In a machine of the character described in- 75 cluding motion transmitting coin controlled mechanism and merchandise delivery mechanism, of motion transmitting means for transmitting motion from one to the other of said mechanisms, said means being arranged to transmit motion from said coin controlled mechanism to said delivery mechanism when said coin controlled mechanism is rendered operative by the insertion of a coin, said means being also constructed to prevent the operation of said delivery mechanism by means other than said coin controlled mechanism, said means including an element movable by the coin-controlled mechanism and limited to movement in one direction by said mechanism, a second element movable with the delivery mechanism, said elements being co-operative in driving the delivery mechanism during permitted movement of the first element when the coin-controlled mechanism is operative, and a stationary guard member for said elements, said guard member being inactive in the control of element movements when the coin-controlled mechanism is inoperative.
- 80 3. In a machine of the character described in- 85 cluding motion transmitting coin controlled mechanism and merchandise delivery mechanism, of motion transmitting means for transmitting motion from one to the other of said mechanisms, said means being arranged to transmit motion from said coin controlled mechanism to said delivery mechanism when said coin controlled mechanism is rendered operative by the insertion of a coin, said means being also constructed to prevent the operation of said delivery mechanism by means other than said coin controlled mechanism, said means including an element movable by the coin-controlled mechanism and limited to movement in one direction by said mechanism, a second element movable with the delivery mechanism, said elements being co-operative in driving the delivery mechanism during permitted movement of the first element when the coin-controlled mechanism is operative, and a stationary guard member for said elements, said guard member being inactive in the control of element movements when the coin-controlled mechanism is operative and cooperative with said elements to prevent element movement when the latter mechanism is inoperative.
- 90 4. In a machine of the character described in- 95 cluding motion transmitting coin controlled mechanism and merchandise delivery mechanism, of motion transmitting means interposed between said mechanisms for transmitting motion from one to the other of said mechanisms and including a rotatable member rotated by said coin controlled mechanism in one direction to transmit motion to said delivery mechanism, means for preventing rotation of said member in an opposite direction, and means for transmitting motion from said member to drive said delivery mechanism when said member is rotated by said coin controlled mechanism and for preventing operation of said delivery mechanism by means other than said member, said means including an element movable with the delivery mechanism and co-operative with the rotatable member to drive said mechanism during member permitted movement, and a stationary guard member for the element and rotatable member, said guard member being inactive in the control of element movement during permitted 100 rotation of said member and co-operative with the element and rotatable member to prevent element movement when the coin-controlled mechanism is inoperative.
- 105 5. In a machine of the character described in- 110 cluding motion transmitting coin controlled mechanism and merchandise delivery mechanism, of motion transmitting means interposed between said mechanisms for transmitting motion from one to the other of said mechanisms and including a rotatable member rotated by said coin controlled mechanism in one direction to transmit motion to said delivery mechanism, means for preventing rotation of said member in an opposite direction, and means for transmitting motion from said member to drive said delivery mechanism when said member is rotated by said coin controlled mechanism and for preventing operation of said delivery mechanism by means other than said member, said means including an element movable with the delivery mechanism and co-operative with the rotatable member to drive said mechanism during member permitted movement, and a stationary guard member for the element and rotatable member, said guard member being inactive in the control of element movement during permitted 115 rotation of said member and co-operative with the element and rotatable member to prevent element movement when the coin-controlled mechanism is inoperative.
- 120 6. In a machine of the character described in- 125 cluding motion transmitting coin controlled mechanism and merchandise delivery mechanism, of motion transmitting means interposed between said mechanisms for transmitting motion from one to the other of said mechanisms and including a rotatable member rotated by said coin controlled mechanism in a forward direction to transmit motion to said delivery mechanism when said coin controlled mechanism is made operative by the insertion of a coin, means for preventing backward rotation of said member, and means for transmitting motion from said member to drive said delivery mechanism when said member is rotated in a forward direction and for preventing rotation of said member in said forward direction by means other than said coin controlled mechanism, said means including an element movable with the delivery mechanism and co-operative with the rotatable member to drive said mechanism during member permitted movement, and a stationary guard 130 member for the element and rotatable member to prevent element movement when the coin-controlled mechanism is inoperative.
- 135 7. In a machine of the character described in- 140 cluding motion transmitting coin controlled mechanism and merchandise delivery mechanism, of motion transmitting means interposed between said mechanisms for transmitting motion from one to the other of said mechanisms and including a rotatable member rotated by said coin controlled mechanism in a forward direction to transmit motion to said delivery mechanism when said coin controlled mechanism is made operative by the insertion of a coin, means for preventing backward rotation of said member, and means for transmitting motion from said member to drive said delivery mechanism when said member is rotated in a forward direction and for preventing rotation of said member in said forward direction by means other than said coin controlled mechanism, said means including an element movable with the delivery mechanism and co-operative with the rotatable member to drive said mechanism during member permitted movement, and a stationary guard 145 member for the element and rotatable member to prevent element movement when the coin-controlled mechanism is inoperative.
- 150 8. In a machine of the character described in-

- member for the element and rotatable member, said guard member being inactive in the control of element movement during permitted rotatable member movement and co-operative with 5 the element and rotatable member to prevent element movement when the coin-controlled mechanism is inoperative, whereby the operation of said delivery mechanism is prevented except when operated by the forward turning of said member when driven by said coin controlled mechanism.
5. In a machine of the character described including manually operated motion transmitting mechanism, coin controlled means for controlling the operation of said mechanism, and merchandise delivery mechanism, of motion transmitting means interposed between said mechanisms for transmitting motion from one to the other of said mechanisms and including a rotatable sleeve member limited to rotation in one direction by said motion transmitting mechanism when made operative by inserting a coin in said coin controlled means, a member adapted to be rotated by said sleeve and operatively connected to said delivery mechanism, a one way connecting means between said sleeve and member, said means including an element movable by the sleeve member, a second element movable with the delivery mechanism, said elements being co-operating in driving the delivery mechanism during permitted movement of the first element when the coin-controlled means is operative, and a stationary guard member for said elements inactive in the control of element movements when the coin-controlled means is operative and co-operating with said elements to prevent element movement when the coin-controlled means is inoperative.
6. In a machine of the character described including motion transmitting coin controlled mechanism, and merchandise delivery mechanism including a gear for operating the same, of motion transmitting means interposed between said coin controlled mechanism and said gear and including a sleeve in opposed relation to said gear and adapted to be rotated in a forward direction by said motion transmitting coin controlled mechanism, means for preventing rotation of said sleeve in a backward direction, a shaft to which said gear is secured and upon which said sleeve is free to turn, a block secured to said shaft and formed with a peripheral notch, a fixed ring member surrounding said block, and a stud member on said sleeve projecting into said notch, said ring member being inactive in the control of block and stud member movements when the coin-controlled mechanism is operative and co-operative with the block and stud member to prevent block movement when the latter mechanism is inoperative, whereby when said sleeve is rotated in a forward direction, said stud member will be moved toward one end of said notch and drive said block in a forward direction to transmit forward motion from said sleeve to said gear and operate said delivery mechanism, and whereby a forward turning of said gear by power applied to said delivery mechanism will cause a wedging of said stud member within the opposite end of said notch between said block and ring and lock said gear against forward rotation.
